G. J. DE G. GARCIA.

MEANS FOR ELECTRICAL TRANSMISSION OF DESIGNS, FIGURES, AND PHOTOGRAPHS.
APPLICATION FILED FEB. 28, 1908.

906,405.

Patented Dec. 8, 1908.

UNITED STATES PATENT OFFICE.

GUILLERMO J. DE GUILLÉN GARCIA, OF BARCELONA, SPAIN.

MEANS FOR ELECTRICAL TRANSMISSION OF DESIGNS, FIGURES, AND PHOTOGRAPHS.

No. 906,405.

Specification of Letters Patent.

Patented Dec. 8, 1908.

Application filed February 28, 1908. Serial No. 418,354.

To all whom it may concern:

Be it known that I, GUILLERMO J. DE GUILLÉN GARCIA, engineer, subject of the King of Spain, residing at Barcelona, in the Province of Barcelona and Kingdom of Spain, have invented certain new and useful Improvements in Means for Electrical Transmission of Designs, Figures, and Photographs; and I do hereby declare the following to be a full, clear, and exact description of the invention, such as will enable others skilled in the art to which it appertains to make and use the same.

It is already known that for transmitting designs, figures and portraits to a distance, there are employed two telegraphic stations with or without wires, of any system, wherein the manifolder of the sending station and the Morse apparatus of the receiving station are substituted by synchronical drums, or in other words, that they are of the same dimensions and revolve at the same speed imparted thereto by a clock motion or other equivalent device or mechanism.

Each drum surface is in contact with a style and both styles are caused to print on the respective drum a helical line of the same path and diameter,—i. e., absolutely identical to one another. This result is obtained either by moving the styles parallel to themselves or by moving the drums upon their axes.

According to my invention I cover the transmitting or sending drum with a layer or plate of bichromate-gelatin upon which it has been reproduced and caused to become high-relief the photograph or design comprising the shades to be transmitted. Any other arrangement under which the relief represents the shadows or shades may be employed. Furthermore, I introduce in the transmitting apparatus several plates or contacts in electrical connection with disks tangentially arranged on a roller or brush inserted in the electrical circuit. The style is located at the end of a simple or multiple lever, the other end of which may rest upon and make contact with one of the plates or it may rest out of contact.

All the disks are rotative; one of them is smooth and the others are toothed or scratched; each of these is uniformly toothed throughout its circumference but the teeth of one disk are different in number as compared with the other disks, so that in a given

time each disk makes a number of contacts which generate a given number of currents or series of Hertzian waves and produce on the receiving apparatus points or lines of a given length, more or less separated from each other, which reproduce the shadows of the original represented by the relief.

A further object of my invention is to provide a mechanism to control the movement of the drums of both the transmitting and receiving apparatus; the latter runs with a more accelerated movement than the former, but at the end of the revolution it stops, and by means of an electrical connection it goes on with the same movement when the transmitting drum begins the next revolution.

In the accompanying drawings I represent the arrangement of parts and apparatus to carry out my invention or improved method for telegraphical transmission of designs and photographs.

Figure 1 is a schematical view of a sending station and Fig. 2 is a schematical view of a receiving station, showing the arrangement for transmitting and receiving designs and photographs and for controlling the movement of the drums. Figs. 3, 4, 5 and 6, are detailed views of the disks —c—^{c₁}—^{c₂}—^{c₃}— on a larger scale. Figs. 7 and 8 are front views of the plates for controlling the movement. Fig. 9 is a section on line —z—_z— of Fig. 1.

Referring to the sending station, Fig. 1, the revolving drum or cylinder —d— is coated with a layer —h— of bichromate-gelatin or other material, having a high-relief photograph or design formed thereon. The style —e— in this case, is carried by the end of a lever —b— connected to a lever —b¹— which moves the lever —b²— by means of the cable or belt —b³— suitably held by pulleys —b⁴—, with the object of amplifying the movements of the style —e— when the latter is lifted or lowered to follow the corrugations or prominent and depressed parts of the design. The shaft —n— of the lever —b²— is connected to one pole of a battery —p—. The lever —b²— carries at one end a small roller —r— to make contact with plates —a—^{a₁}—^{a₂}—^{a₃}— of conductive material, separated from each other, and circularly arranged under the curved path of the roller —r—. On each of these conductive plates —a—^{a₁}—^{a₂}—^{a₃}— is secured a wire —m— with a brush —m¹— which terminates on the

hub of one of the disks —c—c¹—c²—c³— carried by the shaft —g— of ebonite (hard rubber) or other isolating material, and turning all together at the same speed. One of the 5 disks —c— Fig. 3 is quite smooth edged while the disks —c¹—c²—c³— Figs. 2, 5, 6, are toothed, but the teeth of each disk are different in number and shape and are in relation to the length of the line or point to be 10 printed on the receiving apparatus. All of these disks are tangential to a metallic cylinder —i— or brush of any shape which by means of the shaft —i— and wire —6— is placed in the circuit of the battery —p—.

The receiving station, Fig. 2, comprises also a revolving drum or cylinder —d¹— and a style —e¹—, which works in combination with the movements of the style —e— of the sending station and the contacts established 20 by disks —c—c¹—c²—c³— through the coil —10—. The styles —e—e¹— are moved parallel to themselves in respect of the rotary motion of the cylinders —d—d¹—.

When —r— makes contact with one of 25 the plates —a—a¹—a²—a³— the current passes through the respective disks —c—c¹—c²—c³—, each of the disks producing a flow and interruption of currents and Hertzian waves, according to the size and 30 shape of the teeth of their surface.

The plant shown in Figs. 1 and 2, is intended for wireless telegraphic stations; but it may be applied to usual wire telegraphy, by causing the wire —5— Fig. 1 and the wire 35 —11— Fig. 2, to communicate with the earth. Thus, when the receiving station receives the currents or Hertzian waves produced by the contact of the disk —c—, the style —e¹— will produce plain lines which 40 form the black part of the design and when the transmission takes place through disks —c¹—c²—c³—, the style —e¹— will mark points or lines more or less long and spaced apart, which reproduce the different shadows 45 or shades of the design corresponding to the pattern relief.

It is impossible in practice to obtain identical movements for two different apparatus; certainly there are always small differences and the errors grow and grow as they accumulate with one another at each revolution. In order to prevent these errors being accumulated during the rotation of the cylinders —d—d¹—, the cylinder —d¹— at 55 the receiving station revolves somewhat quicker than the cylinder —d— at the sending station, and both cylinders are electrically connected so that —d— communicates with —d¹— at the beginning of each revolution, and —d¹— stops at the end of its revolution and does not recommence its rotation until it receives the communication from —d—. Under these circumstances, although some error may certainly occur at 60 each revolution, these errors are of identical

value, and do not accumulate, so that a quite synchronical motion is produced.

Figs. 1 and 2 show the arrangement to control the movement of the cylinders —d—d¹— which are revolved by means of a small electric motor not shown in the drawings; in any case, —d¹— must run slightly quicker than —d—. The power of the electric motor is transmitted direct to the cylinder —d— through the gear —k—; —d¹— receives its motion through a belt embracing the pulley —l—; the shaft —l— carries at one end a plate —o— with a stopper —o¹— in combination with a rod —q— which forms a part of the armature of a coil —14— and is further controlled by a spring —q¹— so that when the plate —o— turns the stopper —o¹— strikes the rod —q— and this stops the revolving motion of said plate but it does not stop the motor, as the belt slides on the pulley. Cylinder —d¹— does not revolve again till the coil —14— attracts the rod —q— and gets it rid of the stopper —o¹—.

The shaft —3— of the cylinder —d— is fitted at one end with a plate —v— of non 90 conductive material having a metal tongue —v¹— in contact with the shaft —3—. In front of the plate —v— there is a brush —4— in contact with the surface of the plate. At the same time, the surface of the cylinder 95 —d¹—, which is not conductive, carries a metal ring —f— embracing almost the whole circumference, and a plate —f¹— which corresponds to the interruption of the ring; this ring combines with wires —8—9— and the 100 other ring with wires —13—16—.

When the cylinder —d— terminates a complete revolution, a contact takes place between —v¹— and the brush —4—, thus producing in the sending station a current 105 —2—3—v¹—4—5—6— which is transmitted to the receiving station by waves or wires, thus generating in it a current —12—15—14—13—f¹—16—7— as the ring —f— and the plate —f¹— are so disposed that —f— 110 makes contact during the revolution and —f¹— when said revolution terminates. Upon the excitation of the electromagnet —14— it attracts the rod —q—, the plate —o— becomes free, and the cylinder —d¹— 115 goes on its revolving movement. When the current is broken, the rod —q— under the action of the spring —q¹— is placed again in the path of the stop —o¹—.

For transmitting photographs there is produced in the sending apparatus a current —l—n—i—6— which is transferred by waves or by wires to the receiving apparatus wherein a current —12—11—10—9—f—8—7— is generated.

Having thus described the nature of my invention and in what manner the same is to be performed, I declare that what I claim and desire to secure by Letters Patent is:

1. In an apparatus for transmitting photo- 130

graphs or designs in relief which represent the shadows or shades, the combination of conductive plates, a relief design, levers respectively adjacent to the relief and conductive plates, and means whereby when the end of one of said levers runs over the relief, the other end runs over the conductive plates; a receiving drum, an electric circuit comprising the receiving drum and varying from plate to plate according to the position of the lever; and means for producing in the current sent through each plate interruptions which may vary in number in a given time.

2. In an apparatus for transmitting photographs or designs in relief which represent the shadows or shades, the combination of conductive plates separated from each other; levers one end of which runs over the relief while the other end runs over the conductive plate; an electric circuit comprising said receiving drum and varying from plate to plate according to the position of the lever; circular disks, one for each plate, with one of their peripheries constructed smoothly, and the others with varying number of teeth respectively, all of them revolving at the same speed, and having their rims or edges in contact with brushes of the circuit, each disk producing in the current sent therethrough, a number of interruptions varying with the teeth of the disk's rim.

3. Revolving transmission and receiving cylinders, the former running slower than the latter, both cylinders being in circuit, and means for closing this circuit as soon as the transmission cylinder terminates its revolution; means for stopping the receiving cylinder at the end of each revolution and means for releasing it, under the action of the current sent therethrough, when the transmission cylinder terminates its revolution; whereby both cylinders begin their revolution at the same time; and means for employing the same circuit to transmit designs and to control the rotary motion of the cylinder.

4. Revolving transmission and receiving cylinders, the transmission cylinder running at less speed than the receiving one; a plate of non-conductive material on the receiving cylinder in contact with a brush in the circuit of the transmitting cylinder, a metal tongue located on said plate which closes the circuit when the tongue contacts with the brush; means for stopping the receiving cylinder at the end of each revolution; and means to release it when the transmitting

cylinder terminates its revolution; whereby both cylinders begin their revolutions at the same time; and means for employing the same circuit for transmitting designs and for controlling the rotary motion of the cylinder.

5. Revolving transmitting and receiving cylinders, the transmission cylinder revolving at less speed than the receiving cylinder; a plate of non-conductive material on the receiving cylinder in contact with a brush in the circuit of the transmitting cylinder; a metal tongue located on the non-conductive plate to close the circuit and send a current when the tongue touches the brush; a plate with a stopper on the receiving cylinder; a rod engaging said stopper to stop the revolving motion of said cylinder; a coil to withdraw the rod when the circuit is closed on the transmitting cylinder whereby the receiving cylinder is released and both cylinders simultaneously begin a new revolution; and means for employing the same circuit for transmitting designs and for controlling the rotation of the cylinder.

6. A transmitting cylinder and a receiving cylinder both rotatively mounted, the transmitting cylinder rotating slower than the receiving cylinder; a plate of non-conductive material on the receiving cylinder in contact with a brush in the circuit of the transmitting cylinder; a metal tongue disposed in said non-conductive plate to close the circuit and produce a current each time that the tongue touches the brush, a plate provided with a stopper mounted on the shaft of the receiving cylinder, a rod engaging said stopper to the rotation of said cylinder; a coil to withdraw the rod when the circuit is closed whereby the receiving cylinder is released and is free to begin a new revolution simultaneously with the transmitting cylinder, a metal ring partially encircling the receiving cylinder, a plate adapted to fill the space between the ends of the ring; two brushes in frictional contact with the ring and located in the circuit of the coil which attracts the lever carrying the style for tracing the design; and two brushes in frictional contact with the plate and corresponding to the circuit of the coil which moves the rod that stops the motion of the receiving cylinder.

In testimony whereof, I affix my signature, in presence of two witnesses.

GUILLEMO J. DE GUILLEN GARCIA.
